UNITED STATES PATENT OFFICE.

FRANK M. MCCULLA, OF PHILADELPHIA, PENNSYLVANIA, ASSIGNOR TO
FRANK H. LEACH, OF SAME PLACE.

PAPER-BAG MACHINE.

SPECIFICATION forming part of Letters Patent No. 407,300, dated July 16, 1889.

Application filed September 14, 1888. Serial No. 285,402. (No model.)

To all whom it may concern:

Be it known that I, FRANK M. MCCULLA, of the city and county of Philadelphia, and State of Pennsylvania, have invented an Improvement in Paper-Bag Machines, of which the following is a specification.

My invention relates to paper-bag machines; and it consists of certain improvements, which are fully set forth in the following specification and shown in the accompanying drawings, which form a part thereof.

My invention is particularly intended for the manufacture of that class of bags in which the tube or body part is formed with bellows side folds and with what is known as a "square bottom." It is impossible, owing to the construction of these bags, to secure the bellows folds at the bottom with a pasted seam, since their lower edges are under one of the faces of the tube. When the bag is opened, the necessary folds resulting in the bottom cover the edges of the bellows-fold portions and form a fairly tight bottom. The lower edges of the bellows fold are, however, unpasted, and if the hand is thrust into the bag the finger can be readily pushed through the opening left between these unpasted edges, and in fact the entire bellows fold can be laterally pushed out, destroying the utility of the bag. While these defects do not in the majority of cases exhibit themselves, they nevertheless exist and are decidedly objectionable.

The object of this invention is to produce a bag in all material respects and characteristics the same as the present so-called "Union Square Bag," but without the objectionable feature at present possessed by that bag, as pointed out above.

By my improved machine I form my tube in precisely the same manner as in the old form of square bags, with the exception that the bottom edge of the bellows fold is made to project so as to be exposed between the two edges of the faces of the tube and thus to be adapted to receive paste. It will be seen that if the bottom of the tube is bent over on a transverse axis, so as to be pasted on one of the faces of the tube, not only will the two edges of the faces be pasted down securely, as in the old form, but the bellows fold also will be pasted securely to one of the

faces of the tube, so that when the bag is opened every portion of the bottom is sealed tightly and there is no possibility of the contents escaping.

My invention is concerned with the mechanism by which the bottom edges of the bag is cut, and is adaptable to any of the machines now in existence by which the Union square bag may be made—such as the old Union-bag machine or the Stillwell machine, the latter of which is the one part of which is shown in the drawings to illustrate my invention.

Figure 1 is a sectional view on line $x x$ of Fig. 2 of such a paper-bag machine embodying my improvements. Fig. 2 is a plan view of the same. Fig. 3 is an end view of the same, showing the cutting mechanism. Fig. 4 is a view of the detached cutter. Fig. 5 is a plan view of a portion of a paper bag, showing the manner in which its bottom edges are cut. Fig. 6 is a cross-sectional view of the same on the line $y y$ of Fig. 5, and Fig. 7 is a longitudinal sectional view of the same on the line $z z$ of Fig. 6.

A is the table or main frame of the machine.

B are the former-plates for shaping the tube of paper with the bellows folds, which are made by the action of two sets of rollers C C and C' C'.

D is an arm or knife to fold over the sides of the tube upon each other.

D D are the presser-rollers for creasing and flattening the edges of the bag-tube, and are located at or near an opening in the end of the table A and run in contact with each other, but having a central portion slightly recessed to allow the tongue E of the former-plate to extend between them without strain upon the paper of the tube. The end of this tongue is formed into the cutter F, preferably having the usual serrated edge.

G are two bellows-fold cutters extending from frames H on each side of the opening in the table A, above the cutter F, and adjustable to bring its cutting-edge to or from the cutting-edge of the said cutter F by means of the slots h and the adjusting-screws g. Secured at its ends to these frames H is the upper stationary cutter I, preferably inclined

downward and adjustable toward the edges of the side cutters G by means of the slots *i* and adjusting-screws *j*.

In practice I prefer to use a plate J to secure the cutter I to the frames H to give greater rigidity thereto. As shown in Fig. 2, these cutters are arranged a slight distance in front of each other, and this distance may be regulated by means of the adjusting-screws, 5 as heretofore set out, to vary the amount of lap on the tube to receive paste. These cutters are all preferably provided with serrated edges and are located in different planes, with a slight space intervening sufficient to 10 as heretofore set out, to vary the amount of lap on the tube to receive paste. These cutters are all preferably provided with serrated edges and are located in different planes, with a slight space intervening sufficient to 15 admit the paper tube, which is fed to the cutters by the rollers D D. The lower surface of the tube is under the cutter F, and the side cutters G G extend into the bellows side folds, so that the lower edges of the bellows fold 20 are under the side cutters G, while the upper edges and the upper surfaces of the tube are under the top cutter I.

K is a wheel or rotating disk journaled to the side of the frame A and provided with an 25 arm L, extending about the end of the table, so that when this disk rotates in the direction indicated by the arrow in Fig. 1 the arm L, striking upward, forces the paper tube against the cutters, and it is cut in the manner shown 30 in Figs. 5 and 7. Each portion of the paper is cut by that cutter below which it was located, the lower edge *a* by the lower cutter F, the lower edges *b* of the bellows folds by the intermediate side cutters G G, and the 35 upper edge *c* of the bellows folds and the upper portion *d* of the tube by the upper cutter I. As this lower edge of the bellows folds is thus exposed between the upper and lower edges *a d*, it will receive paste and become 40 sealed in the manner desired. From the cutters the bags are conducted by the rollers M to the pasting devices and treated in the usual manner.

My invention is concerned only with the 45 cutting mechanism and lies in the use of the intermediate side cutters G G, whereby the lower edge of the bellows folds is cut so as to be exposed between the upper and lower edges of the bottom of the bag, and is therefore 50 by adapted to receive paste, and in such other points of construction of the cutting mechanism as are dependent upon said cutters.

When the tube has been cut off by the arm or beater L, the short length will be held in 55 the feed-rollers M M. The paste-knife R receives paste from roller S and descends, applying the paste to the edges *a*, *b*, and *d* of the tube. The folding-knife T then descends and folds over the bottom, feeding the completed bag through the pressure-rollers U, which pass it on to the apron W. These devices are well known and need no further description.

I do not limit myself to the mere details of 60 construction.

Having now described my invention, what

I claim as new, and desire to secure by Letters Patent, is—

1. In a paper-bag-tube machine, the combination of a lower cutter and an upper cutter 70 for the outer folds of the paper tube and two intermediate side or bellows-fold cutters, the lower, upper, and side cutters being arranged stationary in different planes and slightly separated for the passage of the paper, the 75 edges of one of said outer cutters projecting beyond the edges of said intermediate side or bellows fold cutters, with a movable beater or cutter transversely movable across the cutting-edges of the stationary cutters. 80

2. In a paper-bag-tube machine, the combination of a lower cutter and an upper cutter for the outer folds of the paper tube and two intermediate side or bellows-fold cutters, the lower, upper, and side cutters being arranged 85 stationary in different planes and slightly separated for the passage of the paper, having their cutting-edges projecting beyond each other and the edges of one of said outer cutters projecting beyond the edges of said 90 intermediate side or bellows-fold cutters, with a movable beater or cutter transversely movable across the cutting-edges of the stationary cutters.

3. In a bag-tube machine, the combination 95 of forming devices for folding the paper into a tube having bellows side folds with cutters for transversely severing the top and bottom layers of the tube, two side cutters projecting into the bellows folds, and a transversely-moving beater or cutter to force the layers of paper forming the bellows fold against the cutters to sever them at each side of the tube. 100

4. In a paper-bag machine, the combination 105 of bellows-fold-tube-making mechanism with a stationary cutter for each of the outer layers of the tube and two side cutters for the bellows-fold layers, and in which said cutters have their cutting-edges projecting beyond each other, substantially as set out, 110 the edges of one of said cutters for the outer layers projecting beyond the edges of the side cutters for the bellows side folds and a transversely-movable cutter or beater adapted to move past the cutting-edges of the first- 115 mentioned cutters to sever the tube.

5. In a paper-bag machine, the combination 120 of bellows-fold-tube-making mechanism with a stationary cutter for each of the outer layers of the tube and two side cutters for the bellows-fold layers, in which said cutters have their cutting-edges projecting beyond each other, substantially as set out, the edges of one of said cutters for the outer layers projecting beyond the edges of the side cutters 125 for the bellows side folds, a transversely-movable cutter or beater adapted to move past the cutting-edges of the first-mentioned cutters to sever the tube, and pasting and folding devices to apply paste and fold over 130 the bottom of the tube.

6. In a paper-bag machine, the combina-

- tion of bellows-fold-tube-forming devices with stationary transverse cutters for the top and bottom layers of the tube and two lateral or side cutters adapted to extend into the bellows folds of the tube and arranged between the other cutters, means to adjust said side or bellows-fold cutters, and a transversely-movable beater or cutter to sever the tube. 5
- 10 7. In a paper-bag machine, the combination of bellows-fold-tube-forming devices with stationary transverse cutters for the top and bottom layers of the tube made relatively adjustable longitudinally to separate or reduce the space between their cutting-edges, and two lateral or side cutters adapted to extend into the bellows folds of the tube and arranged between the other cutters, means to adjust said side or bellows-fold cutters, and 15 a transversely-movable beater or cutter to sever the tube. 20
8. The combination of the lower outer cutter F, upper outer cutter I, intermediate side cutters G, G, arranged with their cutting-edges projecting beyond each other, as set out, with the edges of one of said outer cutters projecting beyond the edge of said intermediate side cutters, and a rotary beater L, adapted to be moved past said cutters F, I, and G to sever the tube. 30
9. In a paper-bag machine, bellows-fold-tube forming and guiding devices, in combination with independent cutters, substantially as set out, for severing transversely the top, bottom, and bellows-fold layers of the tube, the edges of one of the cutters for the outer layers projecting beyond the edges of the cutter for the bellows fold. 35
10. In a paper-bag machine, bellows-fold-tube forming and guiding devices, in combination with independent cutters, substantially as set out, for severing transversely the top, bottom, and bellows-fold layers of the tube at different places in the length of the tube to expose all three layers from one side of the tube, the edges of one of the cutters for the outer layers projecting beyond the edges of the cutter for the bellows fold. 40
- 15

In testimony of which invention I hereunto set my hand.
